POWER HAMMER

Campbell V. Adams, Chicago, Ill.

Application February 4, 1931, Serial No. 513,269

7 Claims. (Cl. 121—30)

My invention relates broadly to power hammers and more particularly to the type of power hammers known as pile hammers, in which a ram is automatically operated by motive fluid supplied to the cylinder to impart motion to the ram. Although I shall refer throughout the present disclosure to this particular adaptation of my invention, it is to be understood that my invention is not to be limited to such use solely, but may 10 be used broadly in the construction of power hammers.

Two different types of power hammers have heretofore been provided. Of these types, the single-acting hammer utilizes the motive fluid on the up stroke of the piston to raise the ram and thereafter to exhaust the motive fluid to permit the piston and the ram to fall by gravity and strike a blow due to acceleration of gravity only. On the other hand, double-acting hammers not only utilize the pressure of the motive fluid against the piston to raise the ram, but also to accelerate the down stroke of the ram. Several different principles of fluid distribution have heretofore been used in the operation of double-acting hammers. One of these principles involves alternately introducing and exhausting a motive fluid of the same pressure from each end of the cylinder to impart motion to the ram. Another principle is where a given quantity of motive fluid may be first admitted to the cylinder beneath the piston to raise the ram and then used expansively at both ends of the cylinder during the down stroke before being exhausted from the upper end of the cylinder only. A still further and third form of motive fluid distribution is where a constant supply of fluid at a uniform pressure is maintained in the lower end of the cylinder below the piston, while for the down stroke a quantity of fluid is admitted from the lower end to the upper end of the cylinder and, because of the limitations of design, must of necessity be used expansively to complete the stroke before being exhausted to atmosphere. My invention belongs largely to this latter type of double-acting hammers, but differs essentially therefrom by the manner in which the fluid is distributed so that the advantages inherent in the construction and operation of both single and double-acting power hammers, as well as many other features, may be combined in a single structure.

The principle of operation of a single-acting hammer advantageously permits the use of a heavy ram but inherently limits the rapidity of succession of blows of the ram, while in the

double-acting type rapidity of succession of blows by the ram is advantageously obtained, but the principle of operation inherently requires a lighter ram to be used. In hammers of either of these types having equal striking energy, the number of blows struck within a given time must be definitely fixed by the ratio of ram weight to dead weight. Furthermore, the established ratio between ram weight and dead weight also determines the area of piston available for lifting the 10 ram. Also, due to the method of fluid distribution in certain of these prior types of power hammers, and particularly in the double-acting compound types, leakage of fluid past the valve or piston has quite frequently prevented the hammer from starting when the motive fluid is admitted and oftentimes has caused the hammer to start operating but without delivering any blows. Many other disadvantages and detrimental effects in the operation of power hammers caused chiefly 20 by the manner of fluid distribution have been experienced heretofore and have caused considerable trouble in their practical use.

My invention is designed with a view of obviating such undesirable limiting factors and detrimental effects and is a radical departure from former types in that the motive fluid is distributed to the cylinder in a manner obtaining exceptionally efficient operation. Primarily, the object of the invention resides in providing a 25 source of fluid supply for maintaining a substantially constant fluid pressure in the lower end of the cylinder below the piston during the operation of the hammer whereby the fluid will act to raise the ram and then at the proper time 30 during the upward movement of the piston fluid will be supplied, at the same pressure, to the upper end of the cylinder above said piston, either by a communicating passage controlled by a valve or indirectly by a source of fluid supply controlled 35 by a valve, to check this upward movement of the ram and to remain in the upper end of the cylinder at a constant pressure during the down stroke of the ram, being exhausted at the end 40 of this stroke by a controlled valve, so that during this down stroke of the ram, fluid of the same pressure will be provided to act simultaneously upon both sides of the piston. Another object of the invention is to provide a simple means of controlling the distribution of the motive fluid in the manner aforesaid, comprising 45 essentially any form or type of valve, capable of operation in the usual way, that is to say, by the movement of the piston, piston rod or extension thereof, or ram, with a simple form of 50

cam arm arrangement, or the like, for actuating the valve as motion is imparted to the piston and ram by the motive fluid. A further object of the invention resides in the efficient construction and arrangement of the cylinder housing and associated parts employed to protect the moving parts, such as the ram and valve mechanism, the cylinder being also enclosed to insulate it from loss of heat and to provide a cool exterior surface, when employing a heated fluid and also to make the hammer adaptable for sub-aqueous work. The housing may comprise several parts so connected together that either part may be removed to obtain access to the valve, ram or cylinder, without removing or even disturbing the mounting of the cylinder within the housing. The following advantages, as well as others, are the result of my invention:

(a) Employment of a heavy ram of the single-acting type capable of operating with the same rapid succession of blows as does a ram of the double-acting type.

(b) The provision of a ram exceedingly heavy in proportion to dead weight for a selected driving energy and velocity of impact, thereby producing a more efficient blow, by reason of less loss of energy during impact, than is possible in other hammers of this type having the same total weight.

(c) Increasing the number of blows within a given time and with the same fluid pressure for a given ratio of ram weight to dead weight.

(d) Greater economy in fluid consumption per unit of energy delivered by the blow.

(e) Causing the wire-drawing or throttling of the elastic fluid during opening and closing movement of the valve to occur at a period in either stroke where the detrimental effects thereof are of no material consequence.

(f) Preventing the leakage of fluid past the valve or piston from hindering the starting operation or from initiating the starting stroke without delivering a blow.

(g) By altering the stroke of the ram, the dead weight may be varied to any desired figure while the fluid pressure, weight of ram, striking energy and velocity of impact may be kept constant.

(h) Providing greater latitude in the design of the hammer to meet specified conditions by increasing or decreasing the stroke without requiring a corresponding change of the number of blows struck per minute.

In order to apprise those skilled in the art how to practice and construct my invention, I shall now describe a preferred embodiment thereof taken in connection with the drawings which form a part hereof.

In the drawings:

Figure 1 is a side view partly in elevation and partly in section, with a portion of the housing removed, of a power hammer embodying my invention;

Fig. 2 is a similar view, but showing a portion of the operating elements of the power hammer in section;

Fig. 3 is a horizontal sectional view taken on line 3-3 of Fig. 1;

Fig. 4 is a horizontal view looking down upon the power hammer, with the cylinder head removed, one-half of the view being in elevation and the other half of the view being in section, to illustrate the manner of operating the valve actuating arms and of supporting the cylinder within the housing;

Figs. 5 to 8, inclusive, diagrammatically illustrate the different positions of the valve and slide bar operating the tripping arms, for a complete cyclic movement of the piston and ram; and

Fig. 9 is a view similar to Fig. 2, showing the cylinder, ram, valve actuating arms, cam and slide bar in elevation.

The power hammer disclosed herein is adapted to be operated by a motive fluid such as steam or compressed air, and is designed principally as a power pile driver, but it is equally applicable for analogous purposes, as, for example, wherever a percussive blow is used, such as in rock drilling, riveting machines, concrete breaking or tamping and the like.

The power hammer comprises a suitable housing 1 provided with opposed guideways 2 in which guides of the usual supporting frame (not shown) are arranged to allow vertical movement of the hammer. Sheaves 33 may be arranged upon a cylinder head 4 to receive cables or like flexible members controlling the vertical movement of the hammer within the frame.

Cylinder block 5 is attached to cylinder head 4. A piston 6 having a ram 7 attached at its lower end is adapted to operate in cylinder 5. The lower end of cylinder 5 is reduced in diameter at 8 to provide an auxiliary chamber 9 receiving an auxiliary piston 10 which forms a seal at the lower end of cylinder 5. The usual piston rings 11 may be employed to assure a tight seal.

Motive fluid for operating the power hammer may be supplied by means of an inlet pipe connection 12, shown in Fig. 4, which communicates with a horizontal passage 13. Passage 13 communicates in turn with an annular chamber 14 disposed in cylinder 5 below piston 6 and directly communicating with the cylinder below the piston at 15. Enlargement 16 formed on cylinder 5 provides a valve chamber 17 opening into chamber 14 at one side. Although I have shown a specific form of valve 18 arranged for actuation in valve chamber 17, it will be specifically understood that the fluid distribution may be accomplished by a valve of any type and location. A rock pin 19, suitably mounted in fluid-tight relation in end heads 25 of enlargement 16, carries an admission trip arm 20 and an exhaust trip arm 21, formed on an enlarged boss 22, mounted exteriorly of enlargement 16, and also carries valve 18 in valve chamber 17. Valve 18 controls the admission and exhaust of motive fluid of two passages. One of these passages, passage 23, is vertically arranged and formed in the wall of cylinder 5 to provide controlled communication between valve chamber 17 and the cylinder above piston 6. The other passage 24 acts as an exhaust for the motive fluid thus supplied to the cylinder above the piston.

Timed movement of valve 18, by means of a slide bar 26 operating trip arms 20 and 21, controls the distribution of the motive fluid to the upper cylinder only, so that during the entire cyclic movement of piston 6 fluid will be supplied at full pressure below the piston, and will be supplied at the same or full pressure above the piston during the cushioning period of up stroke and accelerating period of the down stroke. As piston 6 reaches its position of impact, the motive fluid in the cylinder above the piston is exhausted to atmosphere, or otherwise, through passages 23 and 24. Fluid will again be admitted to the cylinder above the piston appreciably before the end of the upstroke. The purpose of admitting it at this period in the operation is to allow it to act as a

5 cushion for the ascending piston, the motive fluid thereafter remaining in the chamber above the piston during the down stroke. Accordingly, the power hammer disclosed herein is adapted to have motive fluid of substantially the same and constant pressure acting on both sides of the piston during the down stroke. I find, therefore, that ram 7 may be made exceedingly heavy in proportion to dead weight for a selected driving 10 energy and velocity of impact, it being understood that dead weight comprises all parts of the hammer serving to resist the net upward reaction of the fluid against the cylinder head 4. Not only 15 may the ram be made exceptionally heavy in proportion to dead weight, which is one of the advantages of a single-acting hammer, but a more rapid succession of blows may be obtained, which is one of the advantages of a hammer of the double-acting type.

20 The manner in which valve 18 provides for this mode of fluid distribution will be clearly understood by referring to Figs. 5 to 8, inclusive. Fig. 5 illustrates the position of valve 18 at the moment of impact.

25 Assume now that piston 6 is at the position of the beginning of release, as shown in Fig. 8 and is approaching the position as shown in Fig. 5 which is the position of impact, and that it will continue on to the position of drift as shown in Fig. 9. Cam 26' on slide bar 26 engages exhaust trip arm 21 to revolve valve 18 clockwise to uncover passage 23, and thereby to place it in communication with exhaust passage 24. The motive fluid is then exhausted to atmosphere.

30 Assume piston 6 is moving upwardly as shown in Fig. 6. Cam 26' on slide bar 26 functions to operate admission trip arm 20 to rotate valve 18 counterclockwise whereby to close off passage 23 from communication with exhaust 24, and to 35 place passage 23 in communication with valve chamber 17. The particular structure shown places chamber 17 under full fluid pressure at all times. Motive fluid is accordingly supplied to the upper part of cylinder 5 above piston 6 at 40 full and constant pressure prior to the completion of the up stroke of the piston so that a cushion is provided quickly to retard and to check this upward movement. Continued admission of motive 45 fluid above the piston at the same and constant pressure as exists below the piston allows the piston to descend by gravity and to be further accelerated in its descent by the unbalanced pressure existing above the piston until the piston reaches its position of impact, whereupon release 50 of the motive fluid above the piston is effected. Cam 26' on slide bar 26 moves exhaust trip arm 21, as shown in Fig. 8, to rotate valve 18 clockwise to the position shown in Fig. 5, which, of course, exhausts the motive fluid above the piston 55 to the atmosphere.

60 It will be noted that the wire-drawing or throttling of the elastic fluid by valve 18 during any period either in the up or down strokes does not seriously influence the efficiency of the hammer, this being the result of the valve 18 opening and closing at periods either in the up and down strokes, where detrimental effects of this sort are of no material consequence.

65 The power hammer herein described may be 70 constructed with its moving parts, such as ram 6 and valve operating mechanism 20, 21 and 26, exposed for convenience, but on the other hand, they may be totally enclosed as shown for protection against damage or to permit the use of the device 75 for sub-aqueous work, and to insulate the cylin-

der when using a heated fluid, thereby presenting a cool exterior surface to the touch and in addition reducing condensation in the cylinder by keeping the cylinder walls warm.

5 In order to provide relatively quick access to these operating parts, housing 1 has been preferably constructed of two parts 30 and 31, arranged with opposed flanges 32 and 33 on opposite sides, adapted to be clamped together by suitable means, such as bolts 34. Reinforcing bosses 35 are integrally formed and spaced apart to provide increased reinforced bearing surfaces for said bolts 34.

10 Repair work on devices of this type may be greatly facilitated by allowing the cylinder, piston 15 and ram to remain mounted in housing 1 when possible. To accomplish this end, I provide diametrically opposed flanges 36 on cylinder 5, which flanges 36 are adapted to be bolted to the opposed flanges 32 of housing part 30 by means 20 of cap screws 37, as shown in Fig. 4. Flanges 36 are adapted to fit snugly between flanges 32 and 33 as the result of laterally extending shoulders 38 formed on opposite sides of flanges 36, these shoulders providing a seat against which the 25 flanges 32 and 33 may snugly fit. A connecting web 39 carries flanges 36 on cylinder 5. However, at the reduced lower end 8 of the cylinder, this web is reinforced by horizontal enlargements 40. Cap screws 37 do not pass through flanges 33. 30 These cap screws 37 can only be removed after housing cover 31 has been removed.

35 If it is desirable to obtain access to the cylinder, ram or valve parts for the purposes of repair or the like, cap screws 37 need not be removed 35 upon removal of housing cover 31. It will be noted in Figs. 1, 3 and 4 that directly below flanges 36 a ram guide 42 is provided to guide ram 7 in its up and down movements. A guideway 43 is formed on opposite sides of ram 7, as shown in 40 Fig. 3, to receive guides 42. Guides 42 are provided with outwardly extending flanges 44, which are adapted to be clamped between flanges 32 and 33 of housing parts 30 and 31. Cap screws 45 function to secure guides 42 in position. Housing cover 31 may be also removed without removing cap screws 45 or disturbing the mounting of ram 7 within the housing.

45 Slide bar 26 is mounted upon ram 7. A portion of the ram at its upper end is cut away at 47, 50 as indicated in Figs. 1, 3 and 10, and pocket 48 is provided to receive a head 49 carried by slide bar 26. Head 49 is clamped in position in pocket 48 by means of cover plates 51 removably secured 55 in position by means of bolts 52. The slide bar 26 will thus move with ram 7 in its up and down strokes, in order that its cams 26' will operate the trip arms 20 and 21.

60 Although piston rod 53 may be of the same diameter as the auxiliary packing piston 10, I have shown it of smaller diameter and extending 60 downwardly to connect with ram 7 by means of a split bushing 54. A spherical head 55 is formed on the lower end of piston rod 53 so that the upper 65 face 56 of this head may bear against the lower end of split bushing 54, as shown in Fig. 2. The upper end of this bushing 54 may be suitably bolted at 57 to ram 7.

65 Any suitable form of construction at the lower 70 end of the housing may be provided to accommodate the pile. There has been shown, however, a dolly plate 60 carried by a retainer 61 suitably attached to the lower end of housing 1 by means of the same bolts 70 as secure inter- 75

posed seat 62. An impact plate 63 is disposed between the seat and the top of dolly plate 60.

Cylinder head 4 may be secured to the top of cylinder 5 in any suitable way. It will be noted in Fig. 4 that inwardly extending flanges 65 are formed at the upper end of housing parts 30 and 31, but these flanges are so formed as to provide spaces 66 through which inlet pipe 12 and exhaust pipe 67 are carried.

10 It will be understood that various details of construction of the housing may be changed without departing from the scope of the invention.

15 It is not essential that the motive fluid be supplied to the cylinder above the piston from the same source supplying the cylinder below the piston. An exceedingly simple design may be obtained where the source of supply is the same, but the same advantageous results flowing from this form of fluid distribution may be had if separate sources are provided. It has been found that the inherent characteristics of the device disclosed resulting from this form of fluid distribution permit a wider latitude in the design of a power hammer to meet specified conditions. For instance, by altering the stroke, the dead weight may be reduced or increased and the fluid pressure, weight of ram, striking energy and velocity of impact may be kept constant. The number of blows struck per minute may also be kept practically constant if desired, as the stroke is varied, by properly proportioning the design of the cylinder. Not only may be above advantages as well as many others be obtained, but greater economy in fluid consumption per unit of energy delivered by the blow is possible, due primarily to avoidance of exhausting fluid from large clearance space beneath piston 6, and to the lessened initial condensation occurring in the cylinder, as the hot fluid entering the upper end of the cylinder on down stroke comes only in contact with surfaces previously heated by fluid underneath the piston.

Without further elaboration, the foregoing will so fully explain the gist of my invention, that others may, by applying current knowledge, readily adopt the same for use under varying conditions of service, without eliminating certain features, which may properly be said to constitute the essential items of novelty involved, which items are intended to be defined and secured to me by the following claims.

I claim:

1. In a pile driving hammer, a cylinder, a piston operating in said cylinder, a ram driven by said piston, and valve means for supplying motive fluid at uniform pressure to said cylinder below said piston whereby the fluid will act to raise said ram and then at the proper time during the upward movement will be supplied to and remain in said cylinder above said piston substantially at the same and uniform pressure to cushion the upward movement and to assist in accelerating the descent of said ram said valve means releasing the fluid above said piston after said ram has travelled downwardly to the position of impact, maintaining the fluid pressure constant against said piston until said point of impact securing a rapid succession of strokes combined with a heavy ram weight for the total weight and striking energy employed.

2. In a pile driving hammer, a cylinder, a piston operating in said cylinder, a ram driven by said piston, and valve means for supplying a motive fluid at a substantially constant pressure to said cylinder above and below said piston whereby said fluid will be admitted at the proper

time to said cylinder above said piston to cushion the upward movement and to assist in accelerating descent of said ram and will remain therein at the same constant pressure until said ram has descended to the point of impact to secure a rapid succession of strokes combined with a heavy ram weight for the total weight and striking energy employed, whereupon the fluid will be exhausted by said valve means, said fluid remaining in said cylinder below said piston during the descending movement of said piston and acting to raise said ram when said fluid above said piston is exhausted.

3. In a pile driving hammer, the combination of a cylinder, a piston operating in said cylinder, a ram operated by said piston, a source of fluid supply for maintaining a motive fluid of substantially constant pressure in said cylinder below said piston, and valve means for supplying a motive fluid of substantially the same constant pressure to said cylinder above said piston to cushion the upward movement and exhausting said fluid from above said piston as said piston reaches its position of impact whereby motive fluid will simultaneously act on both sides of said piston at a constant pressure until impact of said ram during said downward movement, maintaining the fluid pressure constant against said piston until said point of impact securing a rapid succession of strokes combined with a heavy ram weight for the total weight and striking energy employed.

4. In a pile driving hammer, a cylinder, a piston operating in said cylinder, a ram driven by said piston, means for supplying motive fluid at uniform pressure to said cylinder below said piston whereby the fluid will act to raise said piston, and separate means mechanically engaged by said piston during its movement for controlling the flow of motive fluid regardless of the position of said piston in said cylinder, whereby at the proper time during the upward movement of said ram motive fluid of the same and uniform pressure as exists in said cylinder below said piston will be supplied to said cylinder above said piston, to cushion upward movement and to assist in accelerating descent of said ram, and to be released therefrom by said separate means after said piston has travelled downwardly to its position of impact, maintaining the fluid pressure constant against said piston until said point of impact securing a rapid succession of strokes combined with a heavy ram weight for the total weight and striking energy employed.

5. The combination in a pile driving hammer, of a cylinder, a piston operating in said cylinder, a ram connected to and driven by said piston, means for admitting fluid continuously at a constant pressure to said cylinder below said piston, and means automatically controlled and mechanically operated by said piston for admitting and exhausting fluid to said cylinder above said piston only so that the fluid may act over the entire diametrical area of said piston, the actuation of said last means being so arranged as to relieve said cylinder above said piston of any fluid pressure other than atmospheric during the entire period of upward movement of said piston previous to admission of the fluid to said cylinder above said piston, and subsequently, at the proper time during said upward movement of said piston to allow the fluid at substantially the same pressure as exists in said cylinder below said piston to be supplied to said cylinder above said piston whereby gradually to stop the upward

movement of said piston without compressing the motive fluid, and then to continue permitting the continuous supply of the fluid above said piston at the same pressure as exists below said piston, throughout the entire downward movement of said piston until reaching its point of impact to secure a rapid succession of strokes combined with a heavy ram weight for the total weight and striking energy employed, and then to release the fluid from above said piston to atmosphere and there continue again to keep said cylinder above said piston relieved of all pressure during the accelerating period of upward movement of said piston.

6. In a pile driving hammer, the combination of a cylinder, a piston operating in said cylinder, a ram connected to and driven by said piston, means for supplying motive fluid continuously at constant pressure to said cylinder at the annulus below said piston whereby the fluid will act to raise said piston with uniform acceleration, and separate means automatically controlled and mechanically operated by movement of said piston for controlling the flow of the fluid to said cylinder above said piston whereby at the end of the acceleration period of the upward movement of said piston motive fluid of substantially the same constant pressure as exists in said cylinder below said piston will be supplied to said cylinder above said piston to act over the entire diametrical area thereof to aid in uniformly decelerating and to assist in uniformly accelerating descent of said piston, and to be released therefrom by said separate means, automatically controlled and mechanically operated by movement of said piston, after said piston has traveled downwardly to its position of impact to secure a rapid succession of strokes combined with a heavy ram weight for the total weight and striking energy employed, said sep-

arate means continuing to relieve said cylinder above said piston from fluid pressure until said piston has again ascended to a point where motive fluid is again admitted.

7. In a pile driving hammer, a cylinder, a piston in said cylinder, a ram driven by said piston, a source of motive fluid, and means for supplying the fluid above and below said piston at substantially constant unit pressure, said means including a passage in communication with an annulus in said cylinder below said piston for supplying motive fluid thereto continuously from said source, said means also including a valve and a passage having one end communicating directly with said cylinder above said piston while other end of passage is controlled by said valve, and means moving with the piston for positively operating said valve so that when said piston has moved to a predetermined portion of its upward stroke said valve will connect said passage communicating with said cylinder above said piston with said source of motive fluid whereby to supply motive fluid thereto to check the upward movement of said piston, said motive fluid being admitted to said cylinder above said piston at the same constant unit pressure as to said cylinder below said piston, said piston movable means permitting said valve to remain in its said actuated position supplying motive fluid at constant pressure to said cylinder above said piston until said piston has reached the impact position of its down stroke, said piston movable means thereupon actuating said valve through contact to connect said passage with an exhaust and thereafter continuing to keep cylinder above said piston relieved of fluid pressure during the ascending stroke until cushioning period is again reached.

CAMPBELL V. ADAMS.
